DECORATED COMPOSITE FABRIC

Clarence J. Davies, Detroit, Mich., assignor to
National Automotive Fibres, Inc., Detroit,
Mich., a corporation of Delaware

Application June 5, 1939, Serial No. 277,556

9 Claims. (Cl. 154—47)

The present invention relates to decoration and more particularly to a decorated fabric and an article of manufacture employed in the decoration of fabric.

In the prior application of Cunningham, Serial No. 272,256, filed May 6, 1939, entitled "Decoration," there is disclosed the decoration of cloth by forming embossed designs therein over an abutting layer of unvulcanized rubber, and subsequently vulcanizing the rubber to cause it to retain its embossed or molded shape and to cause it to adhere permanently to the fabric. In said application there was further disclosed the use of a reinforcing sheet material, such for example as paper or a woven sheeting, against the rear surface of the rubber. The purpose of the reinforcing material was to permit the decorated fabric to be tensioned without "pulling out," or flattening the design.

The use of reinforcing material as disclosed in the Cunningham application aforesaid, has been adopted with excellent results generally, but under particular circumstances it has been found that certain disadvantages accrue. Thus for example, when the cloth to be decorated has a certain amount of stretch therein and when the cloth is used in a tensioned condition, as for example in some applications of upholstery to automotive trim interiors, it is found that the presence of the reinforcing material referred to prevents uniform stretch of the fabric. This result is most marked in devices where the fabric employed has a symmetrical design therein, as for example when the fabric is striped.

It is accordingly an object of the present invention to provide a decorated fabric formed by correspondingly embossed fabric and rubber vulcanized together, in which reinforcing means are provided which permit tensioning of the fabric without "pulling out" or reducing the height or effectiveness of the design, and at the same time which will permit uniform stretching of the decorated fabric.

It is a further object of the present invention to provide a material to be employed in the decoration of fabric which lends itself to the accomplishment of the first mentioned object.

It is a further object of the present invention to provide a strip material for decorated fabric which is reinforced against transverse stretching in a manner which permits longitudinal stretching.

It is a further object of the present invention to provide a material to be employed in decorated fabric comprising a strip of uncured

rubber reinforced against stretching in one direction only.

Other objects of the invention will be apparent as the description proceeds, and when taken in conjunction with the accompanying drawing wherein:

Figure 1 is a plan view of a portion of a strip of decorated material;

Figure 2 is a section on the line 2—2, Figure 1;

Figure 3 is a plan view of a somewhat modified form of decorated material;

Figure 4 is a section on the line 4—4, Figure 3;

Figure 5 is a fragmentary section through an embossed decoration illustrating the cooperation of elements;

Figure 6 is a fragmentary sectional view similar to Figure 5, illustrating the result of omitting reinforcing material;

Figure 7 is a view of a tensioned decorated fabric illustrating the condition encountered when no provision is made for longitudinal stretch; and

Figure 8 is a view of a decorated tensioned fabric when manufactured in accordance with the present invention.

The present invention deals with decorated fabrics which are decorated by the method and apparatus illustrated in prior Cunningham applications, Serial Nos. 231,811 and 272,256.

Briefly reviewed, to render the present disclosure complete, this method of decorating a fabric comprises placing a strip, sheet, or area of uncured rubber adjacent the rear face of a fabric to be decorated. By the rear face is

meant the face which is not normally exposed in use. For example, in pile fabrics the face is, of course, the face opposite the pile or nap face. The rubber stock which is employed may be either a rubber stock compounded to blow or become porous on heating, or it may be a non-blowing stock which remains dense throughout the decorating operation. In either case, the fabric is decorated and has a predetermined relief design imparted thereto by applying pressure to the dress or front face of the fabric and at the same time applying heat to vulcanize the rubber. The pressure is applied to the front face of the fabric in whatever predetermined design it is desired to reproduce. It has been found that by this method of decoration it is possible to reproduce a limitless variety of designs, including the reproduction of designs containing a large amount of fine detail. The simultaneous application of heat and pressure causes the rubber to mold or flow into the form of the desired

55

design. At the same time the fabric is caused to conform to the molded surface of the rubber and to become vulcanized thereto.

In the present case I have illustrated only the simplest form of design, which comprises straight parallel beads.

Referring now particularly to Figure 5, I have illustrated a fragmentary section through a decorated fabric, showing a fabric 10 having raised beads 11. The beads 11 are shaped in conformity to corresponding risers 12 formed in a rubberous material 13. As previously stated, the rubberous material in the completed article may be substantially dense, or may be of a spongy character, resulting from blowing of the rubber. A reinforcing material 14 is provided, permanently attached to the rubber 13. As will be noted in this figure, the fabric 10 is separated from the reinforcing material 14 at points *a* by only a very thin film of rubber. In other words, at the points *a* the fabric 10 is vulcanized substantially directly to the reinforcing material 14.

The importance of the reinforcing material 14 will be better appreciated by reference to Figure 6, in which I have illustrated a decorated fabric 10 and a rubber strip 13. In this figure the decorated fabric 10 was initially formed in exact conformity with the showing of Figure 5, with the exception that the reinforcing material 14 was omitted. Figure 6 illustrates the condition which occurs upon tensioning of the fabric 10 transversely of the beads 11. The rubber which forms the basis of the decoration is, as will be appreciated, relatively soft and flexible. When vulcanized it tends to retain its initial shape, but the tendency to retain this shape is not sufficient to resist even moderate tension of the fabric 10. When the fabric 10 is tensioned, the rubber is displaced so that the beads are flattened out substantially as indicated in Figure 6, with the result that the effectiveness of the design, as viewed from the dress face of the fabric 10, is largely lost.

As will be appreciated, in Figure 5 tension of the fabric 10 is transmitted to the reinforcing sheet material 14 at the points *a*, and particularly at the points of attachment between the fabric 10 and the reinforcing material 14 at the edges of the decorated design. The fabric 10, when it is provided with the reinforcing material 14, is therefore capable of withstanding relatively great tension without any substantial loss of effectiveness of the design.

While the provision of the reinforcing material 14 has been found to solve the problem of providing a design which will resist tension of the cloth, another difficulty has arisen. In many applications the fabric which is decorated is in use subjected to substantial tension in both directions. Furthermore, in many cases the fabric has considerable give or stretch thereto. In fact, in all cases, the fabric, if sufficiently tensioned, will stretch or elongate sufficiently to give an undesirable result, which will now be outlined.

Referring to Figure 7, I have illustrated a decorated fabric 10 the decoration being in the form of a plurality of parallel straight beads 11.

In order to emphasize the problem which is overcome by the present invention, I have shown the fabric 10 as a striped cloth, the stripes being indicated at 15. Purely as a matter of illustration, I have shown the fabric 10 in Figures 7 and 8 as strongly tensioned in both directions and applied to a board, such for example as a panel

board, to be employed in upholstery of automobile interiors.

Tension of the fabric in the direction of the arrow *b*, it will be noted, does not reduce the effectiveness of height of beads 11 where a reinforcing material, such as shown at 14 in Figure 5, is employed. However, where this reinforcing material is employed, the tension of the fabric in the direction of the arrow *c* produces an undesirable result. As previously stated, all fabrics will stretch somewhat if tensioned, and particularly in the case of a striped or figured fabric, the unequal stretching which results is undesirable. If the reinforcing material 14 is an ordinary paper or a textile fabric, a uniform tensioning of the fabric 10 in the direction of the arrow *c* will cause more stretch or give in the fabric along the edges of the panel than it does adjacent the decorated beads 11. As a result of this, where the fabric has stripes, such as 15, or is otherwise symmetrically figured, there is a distortion of the design of the cloth.

According to the present invention, the rubber which is employed in decorating the fabric is provided with a reinforcing medium which prevents stretching in one direction and which permits stretching of the rubber in the other direction. It will be appreciated that the present invention is applicable both to elongated strips, such as will be employed in the design shown at 11 in Figures 7 and 8, or in applying other designs, such for example as separated design areas.

Referring to Figures 1 and 2, I have illustrated a strip of thin uncured rubber stock 20, having secured to one surface thereof a reinforcing material 21. According to this embodiment of my invention this reinforcing material may take the form of a strong creped paper. The paper is provided with a unidirectional creping. In other words, the folds are provided, all extending substantially parallel and are indicated by the lines at 22. It will be readily understood that a paper of this nature is readily stretchable in one direction, as for example longitudinal of the strip, and that it will strongly resist stretching in the opposite direction, as in this case, transversely of the strip.

A somewhat different embodiment of my invention is illustrated in Figures 3 and 4 in which the strip area of uncured rubber is indicated at 30 and has embedded therein transverse threads 31. These threads reinforce the rubber 30 against transverse stretching but, as will be readily evident, are ineffective to prevent longitudinal stretching of the strip.

Instead of embedding the threads 31 in the rubber 30, they may be applied to one surface thereof. Instead of threads, other transversely extending elongated reinforcing members of any nature may be employed.

As an alternative it is also possible to obtain the same result by applying an ordinary strong paper or fabric to the rubber and then scoring or cutting the same transversely at close intervals to permit longitudinal stretching of the strip.

Referring now particularly to Figure 8, I have illustrated the appearance of a decorated fabric when made with my improved decorating material and when subjected to sufficient tension in both directions *b* and *c* to substantially stretch the cloth. In this case the stretching of the cloth in the direction of the arrow *b* will not cause the design to lose its effectiveness by reason of reduction of the height of beads or risers 11.

In the event that the creped paper 21 is employed, the paper will strongly resist stretching transversely of the longitudinal direction of the decorations 11. In the event that the rubberous material is in the form illustrated in Figures 3 and 4, the threads or transverse elements 31 prevent transverse stretching of the reinforcing material and the rubber and serve the same purpose as the creped paper.

Tensioning of the cloth 10 in Figure 8 in the direction of the arrow c does not unequally stretch the cloth and thus distort the designs or figures therein. The rubber which forms the basis of the decorations is relatively thin and is quite easily stretched. The reinforcing material, if it is in the form of creped paper as illustrated in Figure 1, is effective to permit elongation of the rubber in conformity with the natural extension of the fabric. Elongation of the design in this instance is accompanied by a corresponding unfolding or loosening of the folds 22 of the creped paper. In the event that the reinforcing material is in the form of transverse threads or the like, it will be apparent that these threads, since they are not interconnected, have no tendency to resist the normal stretching of the fabric. As a result, strips 15, if such are provided in the cloth, will extend parallel after tensioning of the cloth.

It will be noted in Figure 7 that tension of the cloth in the direction of the arrow c results in distortion of the design and unequal spacing of the stripes. It will be readily evident that if the reinforcing material takes any of the other forms suggested in the foregoing, the result will be the same.

While I have illustrated and described several specific embodiments of my invention, it will be apparent to those skilled in the art that various additions, modifications, omissions, combinations and substitutions may be made which will be within the spirit and scope of my invention as defined by the appended claims.

What I claim as my invention is:

1. A decorated slightly elastic fabric adapted to be tensioned in use, having a rubber strip provided with a riser at its front surface secured to the rear face of said fabric in a manner to provide a bead on the front face of said fabric corresponding to said riser, a reinforcing layer adhered to the rear of said rubber strip, said layer adapted to resist transverse stretching but permitting lengthwise elongation of said strip, thereby providing for uniform stretch of said fabric under tension applied thereto uniformly in a direction parallel to said rubber strip.

2. A decorated slightly elastic fabric having a pattern therein adapted to be tensioned in use, having a rubber strip provided with a riser at its front surface secured to the rear face of said fabric in a manner to provide a bead on the front face of said fabric corresponding to said riser, a reinforcing layer adhered to the rear of said rubber strip, said layer adapted to resist transverse stretching but permitting lengthwise elongation of said strip, thereby providing for uniform stretch of said fabric under tension applied thereto uniformly in a direction parallel to said rubber strip.

3. A decorated slightly elastic fabric adapted to be tensioned in use, having a rubber strip provided with a riser at its front surface secured to the rear face of said fabric in a manner to provide a bead on the front face of said fabric corresponding to said riser, said strip being exten-

sible lengthwise upon stretching of said fabric, and means strongly resisting transverse stretching of said strip, while permitting longitudinal stretching of said strip and fabric along said risers, thereby providing for uniform stretch of said fabric under tension applied thereto uniformly in a direction parallel to said rubber strip.

4. A decorated composite fabric adapted to be tensioned in use comprising a facing fabric, a strip of rubber vulcanized to the rear of said facing fabric, and a strip of reinforcing sheeting secured to the rear of said strip of rubber, said facing fabric being slightly stretchable under the tension applied to said fabric in use, said reinforcing sheeting being substantially non-stretchable in a transverse direction and being stretchable longitudinally, said composite fabric being embossed to form beads longitudinally of said strip of rubber and reinforcing material, said reinforcing strip serving to prevent flattening of said beads under tension applied to said fabric transversely of said strip, while permitting longitudinal stretching of said composite fabric along said embossment under tension applied to said fabric longitudinally of said strip.

5. A decorated composite fabric adapted to be tensioned in use comprising a facing fabric, a strip of rubber vulcanized to the rear of said facing fabric, and a strip of reinforcing sheeting secured to the rear of said strip of rubber, said facing fabric being slightly stretchable under the tension applied to said fabric in use, said reinforcing sheeting being substantially non-stretchable in a transverse direction and being stretchable longitudinally, said composite fabric being embossed to form beads longitudinally of said strip of rubber and reinforcing material, said reinforcing strip serving to prevent flattening of said beads under tension applied to said fabric transversely of said strip, while permitting longitudinal stretching of said composite fabric along said beads under tension applied to said fabric longitudinally of said strip, said facing fabric having a symmetrical pattern therein, whereby upon stretching of said composite fabric in the direction of said strip, the original symmetry of said pattern is not distorted.

6. A decorated composite fabric adapted to be tensioned in use comprising a facing fabric, a strip of rubber vulcanized to the rear of said facing fabric, and a strip of reinforcing sheeting secured to the rear of said strip of rubber, said facing fabric being slightly stretchable under the tension applied to said fabric in use, said reinforcing sheeting being substantially non-stretchable in a transverse direction and being stretchable longitudinally, said composite fabric being embossed to form beads longitudinally of said strip of rubber and reinforcing material, said reinforcing strip serving to prevent flattening of said beads under tension applied to said fabric transversely of said strip, while permitting longitudinal stretching of said composite fabric along said beads under tension applied to said fabric longitudinally of said strip, said facing fabric having a pattern including parallel stripes generally perpendicular to said rubber and reinforcing strip, whereby upon stretching of said composite fabric longitudinally of said strip, said stripes tend to remain in parallel relationship.

7. A decorated composite fabric comprising a facing fabric of slightly stretchable material, an intermediate strip of rubber vulcanized to the rear of said facing fabric, a longitudinal em-

bossmen provided in said composite fabric along said rubber strip, and reinforcing means cooperating with said rubber strip and said facing fabric adapted to permit substantially free stretching of said composite fabric longitudinally of said strip, said reinforcing means being substantially non-extensible transversely of said strip whereby to prevent flattening of said embossment under tension applied to said fabric transversely of said strip.

8. A decorated composite fabric comprising a facing fabric of slightly stretchable material, an intermediate strip of rubber vulcanized to the rear of said facing fabric, a longitudinal embossment provided in said composite fabric along said rubber strip, and said facing fabric adapted to permit substantially free stretching of said fabric longitudinally of said strip but preventing flattening of said embossment under tension applied to said fabric transversely of said strip, said reinforcing means comprising one-way creped material secured to said rubber strip, the crepeing extending transversely of said strip.

9. A decorated composite fabric adapted to

be tensioned in use comprising a facing fabric, a strip of rubber vulcanized to the rear of said facing fabric, and a strip of reinforcing sheeting secured to the rear of said strip of rubber, said 5 facing fabric being slightly stretchable under the tension applied in use, said reinforcing sheeting being substantially non-stretchable in a transverse direction and being stretchable longitudinally, said composite fabric being embossed to 10 form beads in said facing fabric longitudinally of said strip of rubber and reinforcing material, the embossment resulting in the formation of thickened risers in the rubber, and the reinforcing strip being united substantially directly to said 15 facing fabric by said rubber at the sides of said risers, said reinforcing strip serving to prevent flattening of said embossment under tension applied to said fabric transversely of said strip, while permitting longitudinal stretching of said composite fabric along said embossment under tension applied to said fabric longitudinally of said strip.

CLARENCE J. DAVIES.
